United States Patent Office

Des. 178,827
Patented Sept. 25, 1956

178,827

KNITTED FABRICS

Arthur B. Burnes, Newton Center, Mass.
Application July 10, 1956, Serial No. 42,190

Term of patent 7 years

(Cl. D47—2)

Fig.1.

Fig.3.

Fig. 2.

Fig. 4.

Figure 1 is a plan of one side of the knitted fabric of my new design, and Figure 2 is a plan view of the opposite side of the knitted fabric.

Figures 3 and 4 are enlarged detailed views of Figures 1 and 2, respectively.

I claim:

The ornamental design for a knitted fabric, substantially as shown.
